LINE FINDER SYNCHRONIZER

David H. Ransom, Montclair, N. J., assignor to
 Federal Telephone and Radio Corporation, New
 York, N. Y., a corporation of Delaware

Application November 14, 1945, Serial No. 628,610

10 Claims. (Cl. 179—18)

1

This invention relates to synchronizing circuits and more particularly to the circuits especially useful in synchronizing line finders.

In a copending application of E. M. Deloraine (51), Serial No. 628,613, filed Nov. 14, 1945, a telephone system is disclosed wherein the telephone lines are all brought into a common electronic distributor. When any line initiates a call, voltages are established on the corresponding distributor electrode which voltages are transferred through to a plurality of link circuits each provided with line finders. One of the line finders operates to make connection with the calling line and transmit the signals on to line selectors which in turn select the called line so that the communication is completed. In the system as disclosed in the above-identified copending application, the line finders are each provided with an oscillator which may operate at a frequency slightly lower than the rotary or repetition frequency of the distributor. The calling line provides a series of pulses which, after processing, may be of constant amplitude. These pulses together with pulses derived from the oscillating circuit are applied to a gate tube which will pass energy only when the pulse from the oscillator and the incoming calling pulses coincide. These passed pulses then serve to synchronize the oscillator with the rotary distributor so that this channel is continuously selected to the exclusion of any other calling line.

According to my invention, I provide means whereby the local oscillator in the line finder circuit operates at a multiple frequency of the distributor rotation. Also, the distributor preferably is supplied with its driving voltage from a source which is a multiple frequency of the distributor frequency and is frequency divided for the purpose of securing more stable operation. The incoming signal then serves to synchronize the local oscillator at the multiple frequency instead of at the actual distributor frequency. By this arrangement, an improved synchronization can be obtained since even if the local oscillator is a part of a cycle out of step with the multiple frequency source, it will only throw off the timing of this synchronizing circuit by a small fraction of the total distributor cycle. This local oscillator frequency is divided so that it will produce control pulses for the line finder gate slightly lower in frequency than the distributor operation until such time as incoming signals are received and synchronizing is effected.

As an alternative feature, in accordance with my invention, the high frequency source which

2

serves to control the distributor may be used directly to synchronize the local oscillator upon receipt of a called signal. In this form, the incoming pulses serve to operate a second gate circuit which in turn will permit application of the master oscillator voltage to the local oscillator of the link circuit for the purpose of synchronization.

It is an object of my invention to provide a 10 multiple frequency oscillator together with a frequency divider as a lower frequency source, and means for synchronizing the multiple frequency oscillator to control said lower frequency source.

It is another object of my invention to provide 15 a high frequency master source together with a local source operating at a slightly different frequency together with frequency dividers for energy from both of the sources and means responsive to signals for synchronizing the master 20 oscillator and the local oscillator to bring the divided frequency of the two sources into synchronism.

It is a further object of my invention to provide 25 a synchronizing system for a line finder of the type in which the line finder is synchronized with the frequency of incoming pulses of a channel by synchronizing a source of energy at a substantially multiple frequency of the pulse repetition frequency and dividing this frequency 30 for synchronizing purposes.

It is a still further object of my invention, in 35 the line finder of the type generally set forth in the objects as above, to provide a means for synchronizing the local oscillator with the master oscillator by means of energy directly therefrom, the application of which is controlled in accordance with the received signals of said channel.

In a system incorporating the features of my 40 invention, the signal or speech currents in the various lines or other channels may be replaced at the exchange by a series of narrow pulses of amplitude corresponding to the amplitude of the original current at the corresponding time. The pulses are produced at sufficient rapidity so that 45 they define substantially the signal envelope. In this manner by allotting different time positions to each line, the signal or voice currents within the exchange may be distributed over a common channel each signal being repeated by a series 50 of pulses displaced in time in accordance with the distributor time position. This distribution may be readily accomplished by means of a cathode ray tube serving as a distributor which will sequentially scan the lines connected to predetermined terminals and respond if there is a

signalling voltage on the line. The channels may be separated by time selection and may be applied through time displacement means and a low-pass filter which serves to reproduce the audio envelope to the same or another distributor also coupled to the lines. The incoming signals may serve to adjust the time displacement means so that they will represent the time difference between the time position of the calling line and the selected called line. The time displacement means may be an actual delay line of some form or an equivalent circuit which, while not producing an actual delay of the signals, will effectively serve to store the energy and release it after a predetermined interval equal to the desired delay. In this manner, the interconnection of any one line with any other line of the system may be accomplished. Upon making this interconnection, the communication signals may pass through the same delay means between the interconnected lines. Furthermore, since the scanning cycle covers each of the lines connected to the distributor, as many simultaneous connections may be made as there are time displacement trunking channels within the exchange.

Preferably, means are provided responsive to the interconnection of the lines to tie up these lines so that they cannot be selected by another subscriber attempting to get the connection. If desired, any conventional type of busy signal may be applied to the subscriber's line when this condition exists so that he will know that he must wait an interval for the line to become free so that he can make the desired connection.

I provide synchronizing means for the line finder in which a frequency higher than the scanning frequency is generated and frequency division is provided to reduce it substantially to the scanning frequency. Thus, a more stable frequency with less phase displacement may be obtained as well as other advantages which are outlined below.

While I have broadly outlined certain objects and features of my invention, a better understanding of my invention and the objects and features thereof may be had from the particular description of an embodiment and certain modifications thereof made with reference to the accompanying drawings, in which:

Fig. 1 is a block diagram illustrating the general circuit set up;

Figs. 2 and 3 are sectional circuit diagrams and views respectively, of a distributor tube used in my system;

Figs. 4 to 8 inclusive, constitute a circuit diagram of a link exchange in accordance with my invention;

Fig. 4 illustrating the common equipment, Fig. 5 showing the pulse forming equipment, Fig. 6 the line finder equipment, Fig. 7 the dial register equipment, and Fig. 8 the line selecting equipment;

Fig. 9 is a diagram illustrating how Figs. 4 to 8 inclusive, should be arranged to illustrate the complete circuit; and

Fig. 10 is an alternative form of circuit including both a common equipment and a line finder circuit which may be substituted as a whole for Figs. 4 and 6 in accordance with my invention.

In an example of a telephone exchange incorporating my system as outlined above, the system may be divided into three parts as shown in Fig. 1: first, all the subscribers' lines, twenty for example, assigned numerals 1 to 20, each of these lines having a subscriber subset equipment such

as 21; second, the equipment common to all line circuits, hereafter referred to as common equipment 22; and third, a group of link circuits one of which is needed for each simultaneous call. Each of the link circuits may be further subdivided into line finder circuit 23, dial pulse forming circuit 24, dial register circuit 25 and line selecting circuit 26. These several major components are interconnected by wires 27-38 inclusive, as shown in Fig. 1. For the sake of simplicity in the description only one-way conversation is illustrated.

As shown, all lines 1 to 20 terminate in common equipment 22. This equipment 22 performs a scanning function, preferably by means of a suitable tube having an electronic beam which sweeps each of the lines in turn.

When one of these lines has a potential indicative of a calling condition, the common equipment 22 applies signals over wires 27 and 28 to all the link circuits in parallel and specifically to the line finder circuit 23 of the first link (chosen for discussion). This line finder 23 operates to find the calling line and transfer the signals over wire 33 to the dial pulse forming circuit 24.

When dialing ensues, this circuit 24 produces dial pulses which are counted and stored in dial register circuit 25. The dial pulse register 25 then serves to control the line selector circuit 26 which may comprise a delay line or other time displacement apparatus.

The incoming speech signals are then transferred from common equipment 22 over wire 23, line finder circuit 23, wire 33, line selector circuit 26 and thence over wire 36 back to the common equipment 22, from whence they are applied to the selected outgoing line. The part of Fig. 1 comprising line finder 23, dial pulse forming circuit 24, dial register 25 and line selector circuit 26 may be considered together as a link circuit. For certain embodiments of the system, a synchronizing frequency may be fed from common equipment 22 over lead 29 to line selector circuit 26 and line finder circuit 23 respectively. The five leads 27, 28, 29, 36 and 37 from common equipment 22 may also be multiplied to other link circuits of the system as shown.

The distributor function of common equipment 22 may be performed by a rotating distributor in the form of a cathode ray tube as illustrated in detail in Figs. 2 and 3. The distributor tube is indicated generally at 39 and may comprise a cathode 40, the usual grid 41, focus and anode electrode 42, horizontal deflector plates 43 and vertical deflector plates 44. Two-phase distributor currents from a suitable sweep control may be applied over leads 45, 46, 47 and 48 to the horizontal and vertical deflector plates respectively, so as to produce a cyclic rotation of the electron beam. At the target end of tube 39 are provided twenty coupling targets 49 to 68 respectively, which are coupled with the individual lines 1 to 20 inclusive. These targets may comprise secondary electron emissive elements associated with a common anode 69 to provide dynodes all having a common output. A mask or screen 70 may be provided, if desired, having apertures therein so that the electron beam will impinge on each dynode only when the beam is aligned therewith thus preventing possible secondary emission from others. The output of the distributor tube 39 is connected from anode 69 over lead 71, then signal isolating circuits hereafter described to leads 27 and 28 which go to 75 the line finder circuit as shown in Fig. 1. The

output from the line selecting circuit 26 may be applied as indicated over line 36 to the grid 41 serving to modulate the beam in accordance with the selected signal energy. Thus, referring to Fig. 1, the output from lead 71 may be applied after suitable delay (produced in line selecting equipment 26 as hereafter described) over lead 36 to grid 41 to provide the desired communication channel between the chosen pair of lines.

The common equipment 22 is illustrated in Fig. 4. For illustrative purposes a base frequency of 10,000 cycles per second has been selected as the scanning rate of the rotating distributor. This frequency is sufficiently high to reproduce voice frequencies with adequate fidelity for transmission of speech. For the twenty-line system the base frequency is derived from a 200 kilocycle stable oscillator 72 preferably crystal controlled. This higher frequency is utilized since it is generally easier to build a more stable oscillator at the higher frequencies than at the lower 10,000 cycle frequency which is to be used. Furthermore, in certain of the modifications illustrated, the 200 kilocycle wave may be utilized for other control purposes. The sinusoidal frequency generated in master oscillator 72 is reduced to the base frequency of ten kilocycles in frequency divider 73.

The output of frequency divider 73 is applied over 90° phase shifter 74 to the vertical and horizontal sets of deflecting plates 43 and 44 of distributor tube 39 herein diagrammatically illustrated. This will serve to rotate the beam at a frequency of 10,000 revolutions per second so that each of the dynodes 49 to 68, illustrated in Figs. 2 and 3 and in this figure, will be scanned once every 10,000ths of a second. Incoming lines 1, 5 and 20 are shown connected to the respective dynodes 49, 53 and 68.

At 21 is illustrated a typical subscriber sub-set (shown connected to line 5) for use in the system according to my invention. Such a sub-set will be connected to each of the incoming lines 1 to 20 inclusive. The voice transmitter 75 is connected in series with dial 76 and the normally open switch hook 77. The receiver 78 is bridged permanently across the line, since, for simplicity of illustration, no separate ringing equipment has been illustrated. Accordingly, the signal for summoning a called subscriber may be applied as a special tone which will be reproduced in receiver 78 to call the listener to the phone.

As in the usual equipment, switch hook 77 is normally open. However, upon initiating a call, the switch becomes closed, completing a circuit in the calling line loop over low-pass filter 79 and the associated lines at the sub-set, applying a negative potential from battery 80 to the associated dynode 53. Normally the dynode electrodes 49 to 68 are at the same potential as anode 69 so no current flows. This negative potential will produce a difference in potential and cause secondary emission current to flow from the dynodes upon impingement of the beam of tube 39 thereon, producing a negative output pulse in output line 71. The pulses are preferably signal modulated to a depth of only 25 to 50 per cent so that there will always be sufficient amplitude to furnish energy to establish and maintain connections regardless of modulating signals. The negative pulses resulting from operation of the selected dynode 53 are fed to the grid of inverter tube 81. The anode circuit of tube 81 is coupled to the grid of clipper tube 82 which serves to clip these pulses at a predetermined

level to pass only the modulated portions of the incoming pulses. Thus, the output of this tube, representing the speech signals, may be substantially 100 per cent modulated. These clipped pulses are then applied to a cathode follower tube 33 and from there to all of the link circuits over the cathode follower output lead 28. A second output is taken across the cathode resistance of inverter tube 81, these pulses being applied to a clipper tube 84 which serves to clip the pulses to a constant level eliminating modulation effects therefrom. The anode circuit of tube 84 is coupled to the grid of a cathode follower tube 85 which serves to apply pulses 86 through common feed resistor 87 over wire 27 to the grid of signal finder gate tube 88 (shown in Fig. 6) of line finder 23 (shown in Figs. 6 and 1) in the first link circuit (now under consideration) and in parallel to the grids of the corresponding line finder gate tubes in all other links. The pulse 86 after passing through resistor 87 may be called 89, so that the pulse actually arriving at the grid of tube 88 and of the other similar tubes is pulse 89. Under the conditions now assumed, when none of the grids of the line finder gate tubes is drawing grid current, pulse 89 is nearly as strong as pulse 86; but under other conditions it may be much weaker than 86. In the absence of any signals on the cathode of this signal finder gate tube 88, the above traced pulse 89 on its grid is insufficient to cause the flow of plate current, because the bias applied to the grid is sufficiently far below cutoff.

A line finder circuit incorporating my invention is illustrated in Fig. 6. A lock-in oscillator 90 which incidentally performs a frequency division and is controlled through the medium of master oscillator 72 is provided. The lock-in oscillator 90 operates at a frequency slightly less than the two hundred kilocycles, its 50 kc. output being fed through a clipper differentiator circuit 91 to a kilocycle synchronized multivibrator 92. Before synchronization the 50 kc. and 10 kc. contents also will differ by corresponding intervals from these frequencies as in the oscillator 90. The output of multivibrator 92 is applied through the differentiating network 93 and 94 to tube 95 which serves to form and amplify the pulses 96. Tube 95 is normally biased beyond cut-off but the leading edge of each square wave output from multivibrator 92 is of sufficient strength to first drive the grid positive on a portion of the square wave. A negative pulse 96 of approximately five microseconds is produced in the plate circuit. A cathode follower tube 97 passes the signal or control pulse 98 to the cathode of line finder tube 88. When the signal 89 on the grid of tube 88 coincides with the above-described selecting pulse 98, the tube 88 conducts and passes a pulse 99 to four places, namely to diodes 101 and 102 and over wire 32 to the line selecting circuit and to tube 109.

This pulse 99 is rectified in tube 102 and fed to an integrating network 103. The negative potential from the integrator is amplified in tube 104 reducing the potential in cathode resistor 105 which is common to tube 104 and tube 106. The reduction of this potential renders tube 104 conductive. Thus, this tube 104 now commences to pass the sine wave from master oscillator 72, which is continuously applied to the grid thereof over line 29. This amplified wave is then passed through phase corrector circuit 107 serving to lock-in oscillator 90 with the master oscillator 72. Accordingly, progression of selection is now

stopped so that the pulses 89 will pass through tube 88 and over network 103 and tube 109 to open line finder gate tube 110 at the correct instants, thus causing the latter to pass the desired signal pulses from wire 28 to wire 33.

Simultaneously, the application of pulses 89 to diode 101 charges circuit 111 and actuates tube 112 which in turn actuates tube 95 to prevent engagement of other line finders as is more fully set forth in the aforementioned copending application.

A combination of a pulse register circuit and associated line selection circuit is shown in Figs. 7 and 8 respectively. Also, a form of pulse forming circuit is illustrated in Fig. 5. The circuits of Figs. 4-8 arranged as shown in Fig. 9 illustrate a complete system incorporating my invention.

Turning first to Fig. 5, the incoming pulses 112a on line 33 with their dialing breaks are passed through network 113, amplifier tube 114, transformer 115, tube 116, integrating network 117 and dial gate tube 118 to an output line 35.

Dial gate tube 118 in Fig. 5 is normally biased to conduction by the voltage on its suppressor from the dial gate control 119, 120 (with tube 119 normally conducting). Pulses passed by transformer 115 are also applied over integrating network 121, tubes 122 and 123, arranged in a time constant circuit, and over rectifier 124 to the grid of tube 119. The time constant of the circuit is such that tube 123 remains operated for a period corresponding to the interval of the dial pulsing. Tube 119 cuts off at the beginning of a series of dial pulses (sending out an ineffective positive pulse) and reoperates at the end, sending out a negative pulse to the dial gate control 119, 120. This negative pulse from tube 123 cuts off tube 119 causing tube 120 to conduct. This biases tube 118 to cut-off locking out the dial gate so that transients and voice modulations or even additional dialing will not disturb the registers (described later). At the same time, a control voltage is sent out over lead 38 biasing the control grid of the output gate tube 152 (Fig. 8) for conduction.

Turning now to Figs. 7 and 8, the output line 35 is coupled to a plurality of trigger circuits 125, 126, 127 and 128. As many of these trigger circuits are provided as there are subscriber's lines. Normally, the right hand tubes of each pair (except for the preliminary one 125) are cut-off, biasing the respective gate tubes 129, 130 and 131 to cut-off on their associated suppressor grids. When a series of dial pulses has been received, it is intended that one of the right hand tubes of the trigger circuits will be left conducting, permitting its gate tube to pass the signal.

The operation of the register may be described as follows: The first trigger circuit 125 has no associated gate and tube 132 is normally conducting. A first pulse over wire 35 from the pulse forming circuit cuts off tube 132 of trigger circuit 125 causing tube 133 to conduct. When tube 133 conducts, a negative pulse is sent from its plate circuit to the grid of the normally conducting tube 134 of trigger circuit 126 cutting off this tube and causing tube 135 to conduct. This operation of tube 135 serves to open the first gate tube 129. The second negative pulse from the pulse forming circuit cuts off tube 135 transferring conduction to tube 134. A negative pulse from the plate of tube 134 cuts off tube 136 restoring the first gate to blocked condition which transfers conduction to tube 137 in the next register 127. The cut-off of tube 134 restores the

first gate tube 129 to blocked condition while the conduction of tube 137 unblocks the second gate tube 130. This cycle is repeated in succeeding registers until the last dial pulse has been sent.

Thus, at the end of dialing only the gate corresponding to the number of dial pulses is left unblocked. Assuming for convenience that line 3 is calling line 5, the second gate 130 will be unblocked. As a consequence then, any pulses which may arrive on the grids of the gate tubes (e. g. over lines 138, 139, etc., described later) will be passed only by gate 130 to the common output wire 140 as will be described in more detail in connection with Fig. 8.

After the calling subscriber has hung up, the release circuit for restoring the registers 125-128 to normal will be operated. This circuit is controlled so that tube 141 is normally cut-off. When the line finder 23 finds a line and locks-in, a signal is applied over line 31 and tube 142 so that the tube 141 conducts. The resulting negative pulse from tube 141 is passed on to tube 143 over condenser 144 but is not effective since tube 143 is already cut off. However, when the line finder releases, tube 141 is returned to its normal cut-off condition, passing a positive pulse to tube 143. This is amplified as a negative pulse in the plate circuit of tube 143 serving to reset all of the register trigger circuits 125-128 to normal.

The manner in which the speech signals are delivered to the selected called (e. g. line 5) will now be considered in detail in connection with Figs. 7 and 8. In this embodiment the speech signals from the calling line are stored and then later released. To determine the proper instant for releasing these stored signals, the equipment counts the pulses which mark the time channels intervening between the calling and called line channels.

In order that this counting may start at the instant corresponding to the calling line's time channel, a synchronizing pulse from the line finder gate tube over line 32 is passed through the shaping amplifier 145 to the synchronizing counter 146. Thereafter, pulses produced in shaping amplifier 147 under control of oscillator 72 carry forward the operation of the system through counters such as 148, 149 and 150 in a manner similar to that described for the register circuits 125-128. Only three counters are shown corresponding to the three described gates 129, 130 and 131, and these counters and gates cooperate to control the instant of release of speech energy to the called line. As the counters operate successively, they apply potentials to wires 138, 139, etc. But if only gate 130 is open, only the potential on wire 139 will pass to common wire 140, thus properly timing the release of speech signals to the called line as will shortly appear.

The incoming energy from the line finder selector gate tube 53 is applied by means of line 33 to a low-pass filter and audio amplifier 148 which serves as a storage means for the incoming speech signals. These speech signals from the output of filter 148 are continuously applied to the control grid of gate tube 152. However, no energy can pass until the completion of dialing when the cut-off bias is removed from control grid of gate tube 152 by the gate control 119, 120 and further until such time as the proper gate pulses are applied from wire 140 to cut-off gate control tube 153 which in turn removes the bias on the suppressor grid of this tube 152. The latter bias will be removed at the proper time relation depending upon which one of the gate tubes 129, 130 is open

at that time. The gate tube 152 will, therefore, be opened at the proper instant in accordance with the incoming line signal so that the energy from storage filter 151 will be passed only at the proper time for application to the outgoing line over lead 36.

The foregoing description covers a complete system incorporating one form of my invention. However, an alternative structure for use in the system using my invention is illustrated in Fig. 10, which shows an alternative arrangement of line finder and common equipment. According to this arrangement, the same master oscillator 72, frequency divider 73 and phaser 74 for controlling the sweep of the beam in tube 39 is used. A slightly modified form of coupling circuit for dividing the signal and synchronizing pulses is shown differing somewhat from that illustrated in Fig. 4. The output negative pulse from distributor 39 is fed over line 71 to an inverter 154 and then into two cathode followers 155, 156. The tube 156 passes the speech signal to line 28 extending to all the links. This signal has not had its modulation depth increased since this function is performed in the link circuits in this form. The control signal is clipped to constant amplitude in a slightly different manner with a clipping circuit comprising duo diode 158 which limits the amplitude of the signal to the grid of the cathode follower 155. This cathode follower feeds through a series resistance 87 to the grids of all the link circuit tubes 88, as explained before.

These tubes are normally biased sufficiently beyond cut-off so that signals 89 alone on the input electrode will produce no change in the output and as before, coincidence with signals derived from the local oscillator is necessary to produce any response. Instead of providing a lock-in oscillator and clipper, I provide in this system a local oscillator 158 operating at two hundred kilocycles $+0.1\%$. The output pulses 89 from the tube 155 are applied to the grid of signal gate tube 88 while the output from oscillator 158 is applied through two frequency dividing multivibrators 159 and 160 to provide the desired pulses which operate through tubes 95 and 97 to apply a selecting signal 98 to the cathode of this same tube 88. The relationship between pulses 89 and 98 will progress as previously described until such time as a selecting pulse 98 on the cathode of tube 88 is applied simultaneously with a control pulse 89 to the grid thereof. Thus, tube 88 passes a pulse 99 through to the grid of tube 161 of a delay flip-flop circuit comprising tubes 161 and 162 thus triggering this flip-flop circuit to its abnormal condition with tube 162 conducting, sending to shaper 163 an abrupt voltage rise. This delay flip-flop circuit has a period of action adjusted by the constants of the grid circuit of tube 161. When it spontaneously returns to normal, the voltage to the shaper 163 drops back abruptly thus completing a long positive pulse to the shaper. The pulse shaper serves to differentiate this pulse and suppress the leading portion, the trailing portion of which has a desired delay. This trailing portion is then amplified and applied to oscillator 158 to synchronize it with the master oscillator 72. The halting of the relative drift of these two oscillators stops the pulse progression of pulse 98 with respect to 89 and serves to lock the line finder to the selected line as previously described. Upon locking into step, the pulses 99 from tube 88 are rectified in rectifier 101 serving to cut-off tube 112 increasing the gain of tube 95 and hence the amplitude of

the pulses 96 and then 98 which are applied to the cathode of tube 88. Because of the fact that a higher frequency is used for the local oscillator, a more stable operation and precise lock-in can be obtained.

The busy gate tubes 164 and 165 operate to impose upon the pulses 89 an upper limit somewhat lower than the limit imposed by clipper 157. This new limit being high to hold a previously engaged line finder but low enough to prevent engaging a new one. In performing this function, tubes 164 and 165 act in a manner similar to duo diode clipper 157. At the instant of arrival of a positive pulse from busy pulse shaper 166 upon the grid of tube 164 it becomes highly conductive and thus acts as a diode to prevent wire 27 from rising above the potential of its cathode. Tube 165 acts as a reverse clipper to discharge the negative potential which would remain at the end of such pulses.

The modification shown in Fig. 10 may be used in place of Figs. 4 and 6 in combination with the circuit arrangement disclosed in Figs. 5, 7 and 8. Furthermore, the synchronizing features shown in connection with line finders in the two modifications illustrated may be used in other types of circuits than the complete telephone or exchange systems shown herein, as will be apparent to those skilled in the art. The use of multiple frequencies for this synchronizing purpose of the type described in particular constitutes one of the principal features of my invention. It should therefore be clearly understood that the specific description of the system and the modifications thereof given herein are merely by way of example and are not to be considered as limitations on the scope of my invention as set forth in the objects thereof and in the accompanying claims.

I claim:

1. A selector circuit for selecting a pulse train, the pulses of which have a predetermined repetition frequency, comprising a source of energy of a frequency slightly displaced from a multiple frequency of said repetition frequency, means for deriving from said energy selector pulses having a repetition frequency slightly lower than said repetition frequency, receiver means for receiving said pulse train and said selector pulses, means in said receiver means for selecting pulses

50 of said pulse train when said pulses and said selector pulses coincide therein, and means responsive to said selected pulses for tuning said energy source substantially to said multiple frequency whereby said circuit will continue to select said pulse train.

2. A method of selecting a pulse train, the pulses of which have a predetermined repetition frequency, comprising providing energy at a frequency slightly displaced from a multiple frequency of said repetition frequency, deriving from said energy selector pulses having a repetition frequency slightly lower than said repetition frequency, selecting pulses of said pulse train when said pulses and said selector pulses coincide, and tuning said energy source substantially to said multiple frequency in response to said selected pulses.

3. A selector system for selecting one channel of a plurality of channels of pulse trains of a predetermined pulse repetition frequency, comprising a local oscillator operating at a frequency slightly lower than a multiple frequency of said repetition frequency, frequency divider means for dividing the frequency from said local oscillator to provide control pulses at a repetition

rate slightly lower than said predetermined repetition rate, gate circuit means normally biased beyond cutoff so that said pulses normally will not pass, means for applying said signal pulses and said control pulses to said gate circuit, means to condition said circuit to pass said channel pulses upon simultaneous application of the pulses thereto, and means responsive to said pulses passed by said gate circuit to bring said local oscillator to said multiple frequency whereby said signal pulses will be continuously selected.

4. In a selector system for selecting one channel of a plurality of channels of pulse channels of a predetermined repetition frequency, the method comprising generating oscillations at a frequency slightly lower than a multiple frequency of said repetition frequency, dividing the frequency of said generated oscillations to provide control pulses at a repetition rate slightly lower than said predetermined repetition rate, mixing said signal pulses and said control pulses to pass said channel pulses upon simultaneous occurrence of said signal and control pulses, bringing said local oscillator to said multiple frequency in response to said passed pulses whereby said signal pulses will be continuously selected.

5. A selector system for selecting one channel wherein each of a plurality of channels of pulse channels of a predetermined repetition frequency, comprising a master oscillator operating at a multiple of said repetition frequency, a local oscillator operating at a frequency slightly lower than said multiple frequency, frequency divider means for dividing the frequency from said local oscillator to provide control pulses at a repetition rate slightly lower than said predetermined repetition rate, gate circuit means normally biased beyond cutoff so that said pulses normally will not pass, means for applying said signal pulses and said control pulses to said gate circuit to condition said circuit to pass said channel pulses upon simultaneous application of the pulses thereto, and means responsive to said pulses passed by said gate circuit for passing energy from said master oscillator to said local oscillator to bring said local oscillator to said multiple frequency whereby said signal pulses will be continuously selected.

6. In a communication system of the type wherein each of a plurality of channels is represented by interleaved signal pulses of a predetermined repetition rate; means for assuring selection of one channel to the exclusion of others of said channels comprising a selector circuit comprising a gate means normally conditioned so that said signal pulses normally will not pass, means for applying said signal pulses to said gate circuit, a local oscillator operating at a frequency slightly lower than a predetermined multiple of the repetition rate, frequency divider means for dividing the frequency from said local oscillator to provide control pulses at a repetition rate slightly lower than said predetermined repetition rate, means for applying said control pulses to said gate means to condition said gate to select and pass pulses, and means responsive to said pulses passed by said gate circuit to bring said local oscillator to said predetermined multiple of the repetition rate whereby said signal pulses will be continuously selected.

7. In a telephone exchange system of the type wherein each of a plurality of lines is coupled to separate distributor terminals and means is provided to scan said terminals successively and cyclically at a predetermined frequency to provide

signal pulses of a predetermined repetition rate in response to the initiation of a call on a line, means for assuring selection of a calling line to the exclusion of others of said lines comprising a source of energy at a multiple of said predetermined frequency, means responsive to energy from said source to provide said predetermined frequency for said scanning, and a line finder circuit comprising a line finder gate tube, normally biased beyond cutoff so that said pulses normally will not pass, means for applying said signal pulses to said gate tube, a local source of energy normally at a frequency slightly lower than the frequency of said first-named source, means responsive to energy from said local source to provide control pulses at a repetition rate slightly lower than said predetermined repetition rate, means for applying said control pulses to said line finder gate tube to lower the bias thereon so that said signal pulses will be selected and passed upon simultaneous application of said signal and control pulses thereto, and means responsive to said pulses passed by said gate tube for applying energy from the first-named source to said local source to synchronize it with said first source whereby said signal pulses will be continuously selected.

8. In a telephone exchange system of the type wherein each of a plurality of lines is coupled to separate distributor terminals and means is provided to scan said terminals successively and cyclically at a predetermined frequency to provide signal pulses of a predetermined repetition rate in response to the initiation of a call on a line, means for assuring selection of a calling line to the exclusion of others of said lines comprising a line finder circuit comprising a line finder gate tube normally biased beyond cutoff so that said pulses normally will not pass, means for applying said signal pulses to said gate tube, a local oscillator operating at a frequency slightly lower than a multiple of the frequency of said repetition rate, frequency divider means for dividing the frequency from said local oscillator to provide control pulses at a repetition rate slightly lower than said predetermined repetition rate, means for applying said control pulses to said line finder gate tube to lower the bias thereon so that said signal pulses will be selected and passed upon simultaneous application of said signal and control pulses thereto, and means responsive to said pulses passed by said gate tube to bring said local oscillator to the multiple frequency whereby said signal pulses will be continuously selected.

9. In a telephone exchange system of the type wherein each of a plurality of lines is coupled to separate distributor terminals and means is provided to scan said terminals successively and cyclically at a predetermined frequency to provide signal pulses of a predetermined repetition rate in response to the initiation of a call on a line, means for assuring selection of a calling line to the exclusion of others of said lines comprising a master oscillator operating at a multiple of said predetermined frequency, frequency divider means for providing said predetermined frequency for said scanning, a line finder circuit comprising a line finder gate tube normally biased beyond cutoff so that said pulses normally will not pass, means for applying said signal pulses to said gate tube, a local oscillator operating at a frequency slightly lower than the frequency of said master oscillator, frequency divider means for dividing the frequency from said local oscillator to provide control pulses at a repetition rate

slightly lower than said predetermined repetition rate, means for applying said control pulses to said line finder gate tube to lower the bias thereon so that said signal pulses will be selected and passed upon simultaneous application of said signal and control pulses thereto, and means responsive to said pulses passed by said gate tube to synchronize said local oscillator with said master oscillator whereby said signal pulses will be continuously selected.

10. In a telephone exchange system of the type wherein each of a plurality of lines is coupled to separate distributor terminals and means is provided to scan said terminals successively and cyclically at a predetermined frequency to provide signal pulses of a predetermined repetition rate in response to the initiation of a call on a line, means for assuring selection of a calling line to the exclusion of others of said lines comprising a master oscillator operating at a multiple of said predetermined frequency, frequency divider means for providing said predetermined frequency for said scanning, a line finder circuit comprising

a line finder gate tube normally biased beyond cutoff so that said pulses normally will not pass, means for applying said signal pulses to said gate tube, a local oscillator operating at a frequency slightly lower than the frequency of said master oscillator, frequency divider means for dividing the frequency from said local oscillator to provide control pulses at a repetition rate slightly lower than said predetermined repetition rate, means for applying said control pulses to said line finder gate tube to lower the bias thereon so that said signal pulses will be selected and passed upon simultaneous application of said signal and control pulses thereto, and means responsive to said pulses passed by said gate tube for applying energy from said master oscillator to said local oscillator to synchronize it with said master oscillator whereby said signal pulses will be continuously selected.
